UNITED STATES PATENT OFFICE.

FRED B. KRALING, OF LISBON, NORTH DAKOTA.

DEVICE FOR GRINDING AUTOMOBILE-VALVES.

1,396,763.

Specification of Letters Patent. Patented Nov. 15, 1921.

Application filed March 8, 1921. Serial No. 450,587.

To all whom it may concern:

Be it known that I, FRED B. KRALING, a citizen of the United States, residing at Lisbon, in the county of Ransom and State of North Dakota, have invented a new and useful Device for Grinding Automobile-Valves, of which the following is a specification.

The device forming the subject matter of this application is adapted to be employed for grinding the valves of internal combustion engines on automobiles.

The invention aims to provide novel means whereby the device may be adjusted properly on the engine, and to provide novel means whereby the tool holders may be rotated.

Figure 1 shows in vertical elevation, a device constructed in accordance with the invention, many parts appearing in section, and sundry parts being broken away; Fig. 2 is a section on the line 2—2 of Fig. 1; Fig. 3 is a section on the line 3—3 of Fig. 1; Fig. 4 is a diagrammatic plan showing the beveled gears of the automatic reversing device; and Fig. 5 is a plan showing a modification.

In carrying out the invention, there is provided a support denoted generally by the numeral S, the support embodying a base 1 carrying a post 2. Set collars 3 are mounted on the post 2 adjacent to the upper end thereof. Intermediate its ends, the post 2 is provided with set collars 4.

A frame F is mounted for horizontal swinging movement on the support S. The frame F comprises a foot block 6 mounted for swinging movement on the post 2 between the collars 4, and a head block 7 mounted for swinging movement on the post, between the collars 3. A base rod 8 is mounted at one end in the foot block 6. One end of a downwardly inclined tie rod 9 is connected to the head block 7. The outer ends of the base rod 8 and the tie rod 9 are secured to a connection 10. The general outline of the frame F is triangular. A tubular shaft 11 is journaled on the base rod 8 and is driven by a pulley 12 or in any other suitable way. The pulley 12 is connected to the shaft 11 by a clutch 75 separated by any suitable means 76, the construction being such that the machine may be stopped at the will of an operator. The shaft 11 is journaled in a bracket 14. The lower end of a brace 15 is connected to the bracket 14, the upper end of the brace being attached to the tie rod 9. The bracket 14 forms a part of a hanger H mounted to

swing in a vertical plane on the frame F. The hanger H embodies a tubular member 16 mounted on the base rod 8 for rocking movement. The tubular member 16 is journaled in a bearing 17, a brace 18 extending between the bearing and the tie rod. A set screw 19 is threaded into the bearing 17 and may be advanced to bear upon the tubular member 16.

Continuing a specific description of the hanger H, it may be stated that T's 20 receive the ends of the tubular member 16. Depending sleeves 21 are carried by the T's 20. Screws 22 are threaded into the sleeves 21. Pressure gages 23 are interposed in the screws 22. The lower ends of the screws 22 are journaled in yokes 24. Shafts 25 are mounted to rotate in the yokes 24, and are provided with cranks 26. Beveled pinions 27 form an operative connection between each shaft 25 and the corresponding screw 22.

The letter C denotes, generally, a carrier embodying ends 28 sides 29 and a bridge 30 connecting the ends 28 of the carrier. The ends 28 of the carrier C are supplied with any suitable means 31, whereby the carrier may be anchored on the engine of a motor propelled vehicle, without removing the engine from the vehicle. A shaft 32 extends longitudinally of the carrier C and is journaled for rotation in the ends 28 of the carrier. Beveled pinions 33 are secured to the shaft 32, adjacent to one end of the shaft. The teeth 34 of each beveled pinion 33 extends through a fraction less than one hundred and eighty degrees, as Fig. 4 of the drawings will show. The teeth of the beveled pinions 33 mesh into a beveled pinion 35, the beveled pinions 33 being so set on the shaft 32 that but one beveled pinion 33 will coöperate at a time with the beveled gear 35. The beveled gear 35 is mounted on one member 36 of a longitudinally extensible shaft, the shaft member 36 being journaled in the carrier C. The shaft member 36 is telescoped into a shaft member 37 journaled in the bracket 14. The construction of the parts 36 and 37 is such, that although telescoping movements between these elements are possible, the rotation of the member 37 will produce a rotation of the member 36. The shaft element 37 is connected operatively with the shaft 11, through the instrumentality of the beveled pinions 38.

Any desired number of slides 39 are mounted for reciprocation on the carrier C

longitudinally of the carrier, for purposes of adjustment. There will be as many slides 39, and attendant parts, as there are valves to grind. The description relative to the 5 slide 39 will, however, proceed in the singular number. The slide 39 is adapted to move for adjustment, longitudinally of the carrier C on the sides 29 of the carrier. A set screw 42 is threaded into the slide 39 and 10 is adapted to engage one of the parts 29 of the carrier, for the purpose of holding the slide in an adjusted position. A bearing 40 is secured as shown at 41 to the lower portion of the slide 39, the bearing being 15 received between the members 29 of the carrier C. A tool holder 43 is journaled for rotation in the bearing 40. On the upper end of the tool holder 43 there is a beveled pinion 44. The beveled pinion 44 meshes 20 into a beveled pinion 45, splined as indicated at 46 on the shaft 32 for adjustment longitudinally of the shaft. The upper portion of the slide 39 carries a depending fork 47, the hub of the beveled pinion 45 being 25 grooved as indicated at 48 to fit in the fork. The fork 47 constitutes means for holding the beveled pinion 45 in mesh with the beveled pinion 44.

In practical operation, the carrier C is 30 anchored on the engine, through the instrumentality of the means indicated at 31, the tool holders 43 having been adjusted longitudinally of the carrier C, so that the tools in the holders may engage properly with 35 the valves of the engine. It is clear that by loosening the set screw 42, each slide 39 may be moved lengthwise of the carrier C until the tool holder 43 is placed properly with respect to the valves to be ground. 40 Rotation may be imparted to the shafts 25, by way of the cranks 26. The beveled pinions 27 rotate the screws 22, and because the screws 22 are threaded into the sleeves 21, the carrier C will be crowded downwardly, the proper pressure being exerted 45 on the valves, and, in this connection, it is to be noted that the operator has within his control, the means whereby he can vary the pressure, at any time. The purpose of 50 the gages 23 is to show that the same pressure is produced on the carrier C at both ends thereof. When the carrier C moves upwardly or downwardly, responsive to a rotation of the screws 22, the shaft member 55 36 slides in the shaft member 37, the driving mechanism remaining intact and operative. Motion is transmitted to the tubular shaft 11 by the pulley 12 or otherwise. From the shaft 11 motion is transmitted to 60 the shaft 36-37 by the beveled pinions 38. The beveled pinion 35 on the shaft member 36, and the beveled pinions 33 on the shaft 32, impart rotation to the shaft 32. From the shaft 32, rotation is transmitted to the 65 tool holders 43, by way of the beveled pinions

44 and 45. The teeth 34 of one beveled pinion 33 leave the teeth of the beveled gear 35, before the teeth 34 of the other beveled pinion 33 engage with the teeth of the beveled gear 35, the inertia of the shaft 32 70 and attendant parts being sufficient to carry each pinion 33 into engagement with the gear 35. Since the beveled pinions 33 are on opposite sides of the beveled gear 35, it will be obvious that the direction of rotation of the shaft 32 will be reversed automatically, the holders 43 being turned first in one direction and then in an opposite direction. 75

The carrier C and parts associated therewith may be adjusted in a variety of ways, to permit the tool holders 43 to coact with the engine valves. Thus, the carrier C may be raised and lowered through the instrumentality of the screws 22. The carrier C 85 may be swung around in a circle, horizontally, since the frame F is mounted for rotation on the support S.

In some automobiles, the axes of the cylinders are not disposed vertically but are inclined with respect to the vertical. When the machine forming the subject matter of this application is used in connection with an automobile, the cylinders of which are inclined, then the hanger H together with 90 the carrier C may be swung on a horizontal axis represented by the base rod 8 of the frame F. By advancing the set screw 19, the hanger H may be held in any position to which it may have been swung. The slides 100 39 may be adjusted along the carrier C so as to space the tool holder 43 properly depending on the location of the valve stems with respect to each other, in the automobile. It is clear that, when a proper tool 105 is inserted into the holders 43, the valves will be rotated and ground upon seats.

In case it is not desired to reverse the direction of rotation of the shaft 32, the beveled pinions 33 of Fig. 4 may be replaced 110 by a single beveled pinion 33^a, as shown in Fig. 5, the pinion 33^a having continuous teeth 34^a.

Having thus described the invention, what is claimed is:—

1. In a valve grinding device, a carrier; a rotatable tool holder shiftable on the carrier; means for rotating the holder; means for raising and lowering the carrier; and means for mounting the carrier for movement in an orbit about an approximately vertical axis. 115

2. In a valve grinding device, a carrier; a rotatable tool holder shiftable on the carrier longitudinally thereof; means for raising 120 and lowering the carrier; and means for mounting the carrier for swinging movement on an approximately horizontal axis.

3. In a valve grinding device, a carrier; a rotatable tool holder shiftable on the carrier 125

longitudinally thereof; means for rotating the tool holder; means for mounting the carrier for movement in an orbit about an approximately vertical axis; and means for 5 mounting the carrier for swinging movement on an approximately horizontal axis.

4. In a valve grinding device, a carrier; a tool holder journaled on the carrier; means for rotating the tool holder; means for exerting a pressure on the carrier; and mechanism for indicating the pressure exerted by 10 the last specified means.

5. In a valve grinding device, a frame; a longitudinally extensible hanger mounted 15 on the frame to swing in an approximately

vertical plane; means for varying the length of the hanger; a carrier on the lower end of the hanger; a rotatable tool holder mounted on the carrier; and driving mechanism extended between the frame and the carrier, a 20 portion of the driving mechanism being extensible to permit an adjustment between the carrier and the frame.

In testimony that I claim the foregoing as my own, I have hereto affixed my signature 25 in the presence of two witnesses.

FRED B. KRALING.
